CLAIM

The ornamental design for a golf bag holder, as shown and described.

DESCRIPTION

FIG. 1 is a top perspective view of a golf bag holder; FIG. 2 is a bottom perspective view of the golf bag holder of FIG. 1;

FIG. 3 is a front elevational view of the golf bag holder of FIG. 1;

FIG. 4 is a rear elevational view of the golf bag holder of FIG. 1;

FIG. 5 is a right side view of the golf bag holder of FIG. 1;

FIG. 6 is a left side view of the golf bag holder of FIG. 1;

FIG. 7 is a top view of the golf bag holder of FIG. 1; and,

FIG. 8 is a bottom view of the golf bag holder of FIG. 1.

The broken lines in the drawings illustrate portions of the golf bag holder that form no part of the claimed design.

1 Claim, 4 Drawing Sheets
